UNITED STATES PATENT OFFICE.

CHARLES A. HABENICHT, OF SAN FRANCISCO, CALIFORNIA.

AUTOMOBILE LOCK.

Application filed April 4, 1921. Serial No. 458,238.

To all whom it may concern:

Be it known that I, CHARLES A. HABENICHT, a citizen of the United States, and resident of San Francisco, county of San Francisco, and State of California, have invented a new and useful Automobile Lock.

The present invention relates to improvements in automobile locks and its object is to provide a lock that works in combination with the switch controlling the ignition system. A further object is to provide a lock that will lock itself automatically every time the switch is turned off so that the driver cannot forget to lock his machine when he turns off the switch. A further object is to provide a lock that may, when unlocked, be taken apart easily, so that the combination of the same can be changed without difficulty in case the key has been lost or stolen. Another object is to provide a lock that may control any number of electric contacts simultaneously, so that the whole electric system of the automobile may be disconnected and locked at the same time. I attain these objects by means of the mechanism illustrated in the accompanying drawing in which Figure 1 represents a horizontal cross-section through my lock attached to the switch board substantially along line 1—1 of Figure 4, Figure 2 a sectional detail view of my lock along the same line, showing the position of the working parts of my lock when the switch is turned on, Figure 3 a sectional detail view of the lock along the same line showing the position of the working parts of the same when the switch is turned off and locked, Figure 4 a front view of the lock as attached to the dash board, Figure 5 a sectional view of the lock taken along line 5—5 of Figure 3 and Figure 6 a perspective view of a key used for my lock.

Referring to the drawing in detail the reader will see that in the coil box (1) attached to the dash board (2) the terminals (3) of the secondary wires of the induction coils, not shown in the drawing, are brought into metallic contact with the terminals (4) of the wires leading to the spark plugs by means of the blades (6) rigidly fastened to the shaft (7). One end of the latter is supported in the coil box as shown at (8), while the other end is supported in the small end of a tapered plug (9) adapted to revolve in the housing (11). A handle (12) is fastened to the opposite end of the plug

(9), by means of which the plug can be revolved in the housing. It will be easily understood that in revolving the plug a person would also revolve the shaft (7) and the blades (6) on the same and thereby open and close the contact between the contacts in the secondary wiring.

The housing (11), of cylindrical shape, is supported in the dash board and is provided with an outer projection (14) which extends into the dash board through the opening (15) but does not penetrate the same to its full depth. This projection locks the housing against rotation.

The locking device for the revolving plug (9) comprises a plurality of sectors (16) pivotally secured in a cut-out portion (17) of the plug on a transverse pin (18) extending through said cut-out portion. The sectors are of equal dimensions and mounted on the pin parallel to each other. They are adapted to pivot on the pin through a limited distance, being limited by the front and rear walls of the cut-out portion, and are normally actuated by the springs (19) to touch the rear wall of the cut-out portion. They are provided in their circumferential portions with small notches (21) which are arranged so that they do not register with each other when the sectors touch the rear wall of the cut-out portion, but can be made to register by the use of a proper key (22) which may be inserted through the hole (23) in the housing and is adapted to push each of the sectors forward against the tension of its spring sufficiently to make all the notches register. When in such a position the notches are adapted to receive the projection (24) of a dog (26) pivoting on a pin (27) supported in the walls of the cut-out portion of the plug (9) and allow said dog thereby to clear the bearing surface of the housing, so that the plug is free to rotate in said housing.

When the key is withdrawn the springs will tend to push the sectors rearward again into contact with the rear wall of the cut-out portion of the plug and in doing so they also tend to throw the projection (24) of the dog out of engagement with the notches (21), the contacting surfaces of the notches and the projection being inclined planes. But the springs will succeed in this tendency only when the plug is in such a position in its bearing that the dog (26) registers with a recess (31) in the housing which it does

only when the switch is off. The recess (31) and the dog (26) are shown in cross-section in Figure 5 and it will be seen that both are rounded off so that, after the insertion of the key has caused the notches to register with the projection of the dog, the mere pressure brought to bear on the dog in the effort to turn the plug will cause the dog to engage the notches and will allow the plug to be turned.

The operation of the device can be easily understood. When the switch is turned on, as in Figure 1, the plug is in the position shown in Figure 2, and in full lines in Figure 3, that is, the dog is in engagement with the notches and prevented from leaving the same only by the fact that it bears against the surface of the bearing of the housing. When the switch is turned off, the dog is caused to register with the recess (31), the springs (19) force the sectors rearward, the dog into the recess, and the notches out of registry with each other, so that the plug is locked. It will be noticed that this locking is done automatically with the turning off of the switch and that no key is necessary for this purpose. When it is desired to use the car again, a proper key has to be inserted and force the sectors forward so that their notches register. Turning the plug by means of the handle will then force the dog into engagement with the notches and allow the plug to turn. The view in Figure 3 shows in dotted lines the locking position of the dog and in full lines the position of the dog when the driver has just begun to turn the plug after inserting his key.

To lock the plug (9) and the housing (11) to each other and to the dash board against rearward motion, so that they cannot be withdrawn by a party trying to tamper with the switch while it is locked, I provide a latch (32) shown in Figure 2, which consists of a threaded cylindrical part (33) and a flattened extension (34) of the same. The cylindrical part is adapted to be screwed into a corresponding threaded recess (36) in the plug which it may reach through a cylindrical hole (37) in the housing and that part of the opening (15) in the dash left unoccupied by the projection (14), all three of which register when the switch is turned on, as in Figure 2. The different holes are arranged so that when the latch is in place, the rear side of the extension is just flush with

the front side of the dash board, so that when the plug is turned, the extension slides along the dash and locks housing and plug against the dash. A slot (39) is provided in the housing connecting with the cylindrical hole (37), to provide a path for the extension (34) when the plug is rotated and to also limit its motion, so as to stop the plug from rotating when it has reached the locking position. A spring (40) between one side of the slot and the extension prevents the latter from turning too easily.

A metal plate (41) secured to the housing is screwed to the dash board as shown at (42) to give a finished surface and additional support to the switch.

I claim:

1. In combination with a supporting board, a detachable switch lock comprising a housing adapted to be inserted in the board having means thereon for locking the same against rotary motion, a switch controlling plug associated with the housing and locking means for the plug, comprising means for locking the plug against rotation and means for simultaneously locking the plug to the housing and the board against longitudinal motion.

2. In combination with a supporting board, a detachable switch lock comprising a housing adapted to be inserted in the board having means thereon for locking the same against rotary motion, a switch controlling plug associated with the housing and locking means for the plug, comprising means for locking the plug against rotation and means for simultaneously locking the plug to the housing and the board against longitudinal motion, the latter means comprising a latch removably inserted in the plug and becoming active when the plug is locked.

3. In combination with a supporting board a switch lock comprising a housing rigidly supported in said board, a switch controlling tapered plug rotatable in said housing, means for selectively locking said plug against rotary motion, a cylindrical hole in the housing and a threaded cylindrical hole in the plug adapted to selectively register with the former, and a latch adapted to be screwed into the threaded hole when both holes register and to lock the plug to the housing when the holes do not register.

CHARLES A. HABENICHT.
